UNITED STATES PATENT OFFICE

PIERRE ANDRE FAVRE, OF CROSNE, FRANCE

METHOD AND APPARATUS FOR FORMING TUBES

Application filed November 3, 1928, Serial No. 317,081, and in Belgium November 17, 1927.

The present invention relates to improvements in methods and apparatus for drawing fusible material into the form of tubes and, more especially, to methods and apparatus for transforming blocks of glass into tubular form.

Glass tubing is, at present, manufactured almost entirely in glass making centers having an abundance of fire-clay, silica and similar raw materials for the manufacture of glass and for the maintenance of furnaces. Countries lacking the necessary furnace and glass making materials have hitherto been forced to import the latter or buy finished tubing. In the one case there has been heavy charges for freight, in the other, equally heavy charges for breakage.

But even in the centers best equipped to turn out tubing, the methods in use leave much to be desired. Thus, it is common practice to melt a charge of glass in a furnace and then, if possible, convert the charge entirely into tubing. If orders are slack, no charge is melted since the furnaces and the tube making machines are, so to speak, interdependent.

Finally, no single machine has as yet been available for permitting changes in the diameter of the tube and of the nature of the glass during the drawing operation.

One of the objects of the invention is to provide a method for making tubing permitting the economical manufacture of the latter in places lacking both in glass and furnace making materials.

Another object is to provide a method for rendering the furnace operation independent of the drawing operation, thus permitting one to be continued while the other is inoperative.

A further object is to replace the prior art methods of forming tubing in which a rotating mandrel or forming-element is used by a method permitting the same result to be obtained with a non-rotating mandrel or forming element.

An additional object is to provide means for varying the diameter of the tubing being drawn in the course of the drawing operation and without interrupting the latter.

A still further object is to provide means for drawing glass tubing of varying composition or color in the same machine without interruption in passing from one type of glass to another.

Still another object is to provide means for sectioning a predetermined length of drawn tubing while the latter is moving through the drawing machine.

Other objects will appear in the course of the detailed description now to be given with reference to the accompanying drawings in which:—

Fig. 1 represents a block of glass adapted for use in the improved method and apparatus; 65

Fig. 2 illustrates the assembly of a guide mandrel and die constructed in accordance with the invention;

Fig. 2a is a section through a preferred form of die;

Fig. 3 is a perspective of a special clamp for supporting the assembly shown in Fig. 2;

Fig. 4 is a partial section through a first form of device for heating the glass blocks; 75

Fig. 5 is a plan of the structure illustrated in Fig. 4;

Fig. 6 illustrates a second form of heating device;

Fig. 7 represents, in elevation, the tube drawing elements;

Fig. 8 is a section taken on line 9—9 of Fig. 7;

Fig. 9 illustrates the tube cutting device in elevation;

Fig. 10 is a section taken on line 11—11 of Fig. 9;

Fig. 11 shows a simplified form of cutting device;

Fig. 12 is a detail, in elevation, of the structures controlling the operation of the tube-cutting device;

Fig. 13 represents, in plan, the structures shown in Fig. 12;

Fig. 14, is an elevation, partially in section, 95 of the heating, drawing and cutting devices in assembled relation.

Referring to Figs. 1 to 5 of the drawings, there is shown a solid block of glass 1 having a central orifice 1¹ therethrough and having 100

a recess on the under face and a projection on the upper face thereof,—a mandrel 2, 3, 4 adapted to receive blocks 1 and formed of ferro-nickel or similar heat resisting material, portion 2 being of slightly less diameter than 1¹, while portions 3 and 4 are reduced to coact with proper suspending clamps,—a heat-resisting tube 5 formed of a material similar to that of the mandrel,—a sleeve 6 attached to rod 5 and permitting variation of the vertical position of a tapered fire-clay or fire-brick die 7 having a circular, oval, triangular, square, polygonal or other desired transverse section,—an infusible disc 8 conforming in shape to the base of block 7 but extending slightly beyond the periphery of the latter,—a pair of hingedly mounted suspending clamps 9¹, 9² adapted to fit into recesses 3 and 4 respectively and to be opened successively to permit blocks of glass to be strung onto mandrel 2, one of said clamps being maintained closed to assure suspension of the mandrel-die assembly,—a pivotally mounted locking device 10 having pairs of oppositely directed arms formed at one end thereof adapted to embrace the arms of clamp 9¹ or 9² and assure the maintenance of one or the other of these clamps in locked position,—a series of blow torches 11 mounted on a common base,—a ring 12 supporting the torch assembly,—balls 13 interposed between the torch base and ring 12,—a link 14,—a pin 15 eccentrically mounted on rotatable disc 15² and adjustable in position along a slot 15¹,—sleeves 16 and 17 limiting the heating action of the torches, sleeve 16 being, preferably, fixed, and sleeve 17, adjustable in position.

It is to be noted that, since the function of clamps 9¹ and 9² is to maintain the mandrel-die assembly rigidly in a predetermined position, it may be desirable to add a third clamp similar to the two already described whereby two of the three clamps may be always maintained closed and a perfect alignment of the mandrel-die assembly so assured. It will be noted further that the rotation of disc 15² results in an oscillatory movement of torches 11, the position of pin 15 being adjusted so that the oscillatory movement of the torch-base corresponds to the distance between any pair of adjacent torches i. e. for a heating assembly containing 10 torches, the distance which the supporting base moves at each oscillation should correspond to $\frac{1}{10}$ of the circumference. Even heating of the entire periphery of the glass-blocks is thus assured. Sleeves 16 and 17 delimit 4 heating zones. In zone A, the glass blocks are maintained at the temperature to which they have been pre-heated by the gases rising from the lower more highly heated zones. Zone B is sufficiently hot to assure the joining of the superposed glass-blocks, and in zone C, the latter become plastic and flow down and over

die 7, 8 into the protection offered by sleeve 17 in zone D.

The proper choice of materials for the die assembly 7, 8 is one of the essential elements in the production of perfect tubing. Cone 7 is best formed of a thin, fine-grained refractory clay, baked at a high temperature and glazed externally. The glazing facilitates the movement of the viscous glass mass over the cone and prevents bubbles of gas from being driven from the latter into the former. Plate 8 should be formed of a metal which neither oxidizes (like iron) nor colors the glass with which it is in contact (like copper). Pure nickel has been found to give the best results. Plate 8 may be mounted as shown in Fig. 2 or may be supported between a pair of stiffening rings 8¹, 8² formed of ferro-nickel, nichrome or the like (Fig. 2^a). Plates thus constructed present a smooth, unalterable, surface of contact for the glass tube being drawn and yield a product having a brilliant internal surface. It is to be understood, of course, that a nickel plated or covered die may be used instead of a solid block of this metal.

Inasmuch as it is intended to give a complete unified description further on of the mode of operation of each of the various units constituting a complete tube-drawing machine in the order in which they function, it suffices merely to remark here, that the purpose of the structures so far described is merely to convert a solid block of glass into a plastic mass and to pass the latter over a die to produce a tube having the sectional form desired. This is accomplished during the passage of blocks 1 through heating zones A, B, C and D in internal contact with die 7, 8.

The form of heating device shown in Fig. 6 differs from the one already described only in the substitution of a furnace 18 heated by electricity, coal, gas, oil or otherwise for the blow-torches shown in Figs. 4 and 5. The mode of operation remains the same. Here, sleeve 16 is suspended from the tap of the furnace, while sleeve 17 is supported on an annular member 17¹ which may be moved upward or downward by turning wing-nuts 17² on threaded-bolts 17³. A pump 70 has been represented in this figure attached to one end of tube 5 and serves to exhaust or to pump air or a gas into or out of the interior portion of the tube being drawn. This pump may also be used in the form of device shown in Figs 2 to 4 and in a manner to be set forth in another part of the specification.

Referring now to Figs. 7 and 8, there is shown an apparatus for drawing the glass tubes formed by passage over die 7, 8 and comprising, a series of rotatable shafts 19 mounted vertically in line with one another and supported by an upright 25¹,—a series of wheels 21 of the same diameter mounted on shafts 19 (three have been shown by way of example) 130

each having a flat-bottomed, asbestos-lined groove 21¹ formed therein,—a sprocket-wheel 22 rigidly connected to the highest of said wheels 21,—a chain 23 engaging with sprocket 22 and driven by a mechanism to be described further on,—a gear 24 rigidly attached to wheel 21,—a train of gears 24¹ driven from gear 24 and each driving a wheel 21,—a series of pins 26,—a series of bent 5 arms 27 pivotally suspended from pins 26,—a series of wheels 28 of substantially the same diameter as wheels 21 and each having an asbestos lined angular groove 28¹ adapted to properly contact with the tube to be drawn,— 10 and a series of weights 29 adjustably mounted on the horizontal portion of bent-arms 27.

From the foregoing it will be evident that the tube descending from die 7, 8 will be seized between pairs of wheels 21, 28 (Fig. 20 13) and will be drawn regularly under the action of a single drive-gear 24 in the direction of the axis X Y of the machine. The distance between wheels 21 and 28 may be changed by shifting their supporting up- 25 rights 25¹, 25², along frame-work 20, 20 and relocking the uprights in position by means of set-screws or the like. Wheel 21 is made flat-bottomed so that the linear velocity of the tubing being drawn should not vary when 30 the diameter of the latter is changed. If the groove in wheel 21 were angular (like that of wheel 28) instead of flat bottomed, the linear velocity of a tube of large diameter would be greater for a given angular velocity 35 of wheel 21 since the points of contact of the tube and wheel would be further from the center of the latter. Wheel 28 may be provided with an angular groove since a better grip on the tube is obtained, the angular form 40 having no effect on the linear velocity of the tube because of the passive rôle (mere pressure) of this element.

To obtain the finished tube, it remains only to section at desired intervals. This is accomplished automatically by the special apparatus shown in Figs. 9, 10, 12 and 13 comprising a pair of rotating knives 30 adapted to section a glass tube, a frame 31 supporting the knife control devices,—guide ways 32 for 45 the movement of frame 31,—a counterbalancing system 33, 34,—a pulley 35 and fly-wheel 36 rotatably supported on frame 20 above the tube drawing assembly and driven from a motor (not shown) by belt 37,—a pinion 38 driven by pulley 35 and driving a gear 39 mounted on a shaft 40,—a pinion 41 keyed to shaft 40 and having teeth formed on only a portion of the periphery thereof whereby either one of two gears 42 and 43 positioned 50 to come into mesh with the teeth of said pinion may be driven thereby,—three large teeth or cams 41¹, 42¹, 43¹ rigidly mounted on pinions 41, 42 and 43 respectively and positioned so that at the instant that partially toothed gear moves out of mesh with

either pinion 42 or 43, large tooth or cam 41¹ engages with tooth 42¹ or 43¹ as the case may be and maintains contact therewith until the small teeth of the other of the two pinions engages with the small teeth on partially toothed gear 41,—a pair of pinions 45, 46 driven by gears 42, 43 and meshing with a double rack 47 rigidly connected to frame 31,—a knife-actuating assembly consisting of a pair of bent levers 49 pivotally mounted on shafts 50, each carrying a pair of pulleys 51, 51¹, cables 52 driving pulleys 51 from a double pulley 53, cables 54 extending from pulleys 51¹ to a pair of pulleys 55 mounted in driving relation to knives 30, a shaft 56 carrying double-pulley 53, a pulley 57 driving shaft 56 and driven from a motor (not shown), a connecting rod 61 pivotally connected at 49², 49² to arms 49¹, 49² of levers 49 and tending to be maintained towards the right by spring 60 (position where knives 30, 30 are separated), a species of inclined cam 58 rigidly (or, if desired, adjustably) mounted on frame 20, a finger 59 positioned so as to contact with the left hand surface of cam 58 during the descent of frame 31 and limited in its pivotal towards the left by shoulder 59², a spring 59¹ tending to maintain finger 59 in contact with shoulder 59² but permitting said finger to bend towards the right when it rides over the right hand surface of cam 58 during the ascending movement of frame 31,—and an assembly for gripping the tube, at the moment that knives 30, 30 section the latter, consisting of a fixed jaw 71 adjustable in position 100 by means of a threaded rod 72 and having its glass contacting surfaces lined with asbestos, and a movable jaw or lever 73 tending to move towards its open position under the action of spring 75 and towards its closed position under the pull exerted by arm 49¹ on a spring 74.

Shaft 40 may be arranged to drive the tube-drawing unit by mounting a sprocket 48 in driven relation thereto and passing 110 chain 23 over said sprocket.

The manner in which the various units of the complete machine operate is as follows: A number of glass blocks 1 which have just been made by flowing, pressing, or casting 115 and which are still hot, or which have been reheated in any convenient form of furnace, are mounted on mandrel-die assembly 2, 7, 8. This is accomplished by opening clamp 9¹, lowering a block between clamps 9¹ and 9², closing clamp 9¹ and opening clamp 9² and continuing until a column of blocks of proper height is obtained. The blocks in zone A are maintained hot by the rising products of combustion, and by conduction and radiation, in zone B adjacent blocks fuse and in zone C they become plastic and flow by gravity, under the pressure of the blocks above them, over die 7, 8. The elongated mass depending from 7, 8 hardens as it leaves the furnace 120 125 130

under the cooling action of the air. If desired, jets of air may be directed against the extruded or drawn tube to increase the cooling and hardening effect. The first tubing 5 extruded is sectioned at the level of the second platform (Fig. 14) and rejected (since it is generally imperfect) and the extremity of the tube thus obtained is introduced between drawing wheels 21 and 28 which draw the 10 tube out and,—since the speed of wheels 21 may be regulated by manipulating a rheostat or other convenient form of speed regulating device (not shown) attached to the motor in driving relation to said wheels,—produce 15 tubing of any desired diameter (or sectional measurement) the pressure exerted by wheels 28 being adjusted by moving weights 29. The tube then enters the tube-sectioning unit and descends between cutters 30, 30, rotating in 20 opposite directions, which descend at the same speed as the tube. When frame 31 arrives at the point in its downward course where finger 59 engages with the left hand surface of cam 58, left-hand arm 49¹ will exert 25 a pull on right-hand arm 49¹ through the intermediary of link 61 and cause knives 30, 30 to approach one another. At the same time movable jaw 73 will be drawn by spring 74 towards its gripping position. The various 30 operating elements may be designed so that jaw 73 grips the tube just prior to its being sectioned by knives 30, 30. During the downward movement of frame 31, partially toothed gear 41 is in mesh with one of the 35 pinions 42, 43, and the other of these two pinions is being rotated (while out of contact with gear 41) passively, and in the opposite direction as its mate, by rack and pinion assembly 45, 46, 47. Immediately after the 40 tube is sectioned, the small teeth of gear 41 move out of mesh with the small teeth of the pinion with which they have been in contact during the descending movement and carriage 31 comes to rest under the action of its counterweights. Gear 41, at this stage, 45 rotates freely (i. e. out of engagement with pinions 42 and 43) and continues to do so until large tooth or cam 41¹ contacts with either 42¹ or 43¹, as the case may be, and 50 brings the small tooth of the pinion which had remained inactive during the descending movement into exact alignment for meshing smoothly with the small teeth of gear 41. Otherwise expressed, large teeth 41¹, 42¹, 43¹ 55 serve merely to assure smooth engagement between the small teeth on gear 41 and those on pinions 42 and 43. The upward movement then begins. During the upward movement, finger 59 contacts with the right hand side of 60 cam 58, is bent towards the right (Fig. 10), and snaps over the latter back into vertical position under the action of spring 59¹, spring 60 maintaining knives 30, 30 in separated position. When frame 31 reaches the top 65 of its course, tooth 41¹ meshes with either 42¹

or 43¹ and said frame descends in the manner described in connection with the reversal of the descending movement. It is to be understood, of course, that the toothed and smooth portions of gear 41 should be spaced to assure proper timing of the reversing movements and that the various gears should be chosen so that cutters 30, 30 move downward at the same speed as the tube.

If it be desired to change the color or the composition of the tubing being drawn, it suffices merely to mount glass blocks of the composition or color desired on mandrel 2 in continuity with those being drawn and to cut off and reject the length of tube of mixed composition or color adjacent the point of junction. In practice, it is found, that glasses of very different composition will fuse together and produce tubing, the rupture, if any, occurring after cooling and extending over only a short length.

If, in the course of the drawing operation, it be desired to vary the diameter of the tube, it suffices only to change the velocity of wheels 21, 28 and increase or decrease 90 the amount of heat being furnished to blocks 1 by the blow-torches or other source of heat.

When die 7, 8 is elliptical or oval the tube formed thereby is of a corresponding shape 95 and by exerting suction or pressure on the inside of the tube (pump 70, Fig. 6) the flatness of the latter may be diminished or increased during the drawing operation.

In the special form of cutting device represented in Fig. 11, the knives represented in Fig. 10 are replaced by a pair of metal flexible arcs 63 which section the heated tube by their local chilling action. Here finger 59 actuates a lever 66, pivoted at 65, to operate a pair of links 62, 67 so as to oscillate a pair of arms 62¹, 68 against the resistance offered by spring 60 and bring arcs 63, 63 supported by flexible elements 63¹, 63¹ into contact with the tube. The timing of the oscillatory movement of elements 63, 63 is effected by cam 58 in precisely the same way as described in connection with the cutting device shown in Fig. 10.

The various types of apparatus lend themselves readily to producing tubing with a distinctive colored stripe or mark, it being necessary to merely interpose a ring, a ball or a rod of colored glass between adjacent blocks 1 or to insert the former in any way 115 desired into a recess formed in the latter in the manner represented by rod 1² in Fig. 1.

From the foregoing, it will be seen that the hereinabove described method and apparatus permits non-glassmaking countries 120 to import conveniently transportable glass-blocks and manufacture as desired tubing of any desired size, section, composition or color. Glass manufacturers are provided, for the first time, with means for running their 130

furnace and tube-making departments independently, it being possible to make and stock blocks in any quantity during slack demand and later reheat and feed the blocks directly into the tube making machine. Finally, a single apparatus is provided permitting the continuous production of tubing of varying diameter, color and composition during the drawing operation.

10 The inventor is aware of the existence of devices in which a tube is formed by flowing molten glass onto an inclined rotating mandrel through which air is being blown. His device replaces the rotating, by a stationary, forming element and eliminates the necessity of introducing air into the center of the tube, the latter operation being purely optional. It is to be noted further that since the tube is drawn vertically an upward draft is produced through the bore thereof tending to effect a "blowing" action.

In the following claims, the word "fixed" forming element is employed as meaning "non-rotating" as distinguished from the rotating elements used heretofore.

15 1. The method of forming continuous vitreous tubing which comprises heating a hollow solid vitreous mass in internal contact with a fixed forming element, and drawing the tube thus formed over said element.

20 2. The method of forming vitreous tubing of diverse sectional area which comprises the steps of forming a block of solid material, heating said block until it flows, and drawing the viscous mass end-wise over the entire periphery of a fixed forming-element at a rate varying in accordance with the sectional area desired and varying the amount of heat supplied to said block in accordance with the rate at which the drawing operation is being effected.

25 3. The method of forming vitreous tubing comprising the steps of forming a block of solid material having an orifice therethrough of relatively small sectional area, heating said block until it flows, and simultaneously enlarging said orifice and drawing out what was formerly the block while the latter is plastic.

30 4. The method of forming vitreous tubing comprising the steps of forming a block of solid material having an orifice therethrough of relatively small sectional area, heating said block to plasticity, and drawing it endwise, while plastic, over a fixed forming element of greater sectional area than that of the orifice formed therein whereby a tube having an orifice of relatively large sectional area is produced.

35 5. The method of forming vitreous tubing which comprises the steps of mounting a hollow, solid, vitreous mass on a mandrel having a portion thereof of progressively increasing section, and heating said solid vitreous mass so that its temperature is high-

est at a point adjacent that portion of the mandrel having the largest section.

6. The method of forming vitreous tubing which comprises the steps of mounting a hollow solid vitreous block on a mandrel having a portion of its surface formed of metal, heating said block until plastic, and drawing the plastic mass endwise over the mandrel in contact with said metallic mandrel portion.

7. The method of forming marked vitreous tubing which comprises heating a solid block composed of vitreous material of different compositions in internal contact with a fixed forming element, and drawing the tube thus formed over said element.

8. In a tube drawing device having a suspended elongated forming mandrel with means for supporting said mandrel comprising separate clamps mounted in spaced relation adjacent one extremity of said mandrel.

In testimony thereof I have signed this specification.

PIERRE ANDRÉ FAVRE.
